[57] CLAIM

The ornamental design for a suspension shelf display stand, as shown and described.

DESCRIPTION

FIG. 1 is a front elevational view of a suspension shelf display stand showing my new design;

FIG. 2 is a side elevational view thereof taken from the right side of FIG. 1;

FIG. 3 is a top plan view of the suspension shelf display stand shown in FIG. 1;

FIG. 4 is a rear elevational view thereof;

FIG. 5 is a bottom view thereof; and

FIG. 6 is a perspective view thereof.

The side of the display stand not shown is a mirror image of the side shown in FIG. 2.
